US0D1086242S

(12) **United States Design Patent** (10) **Patent No.:** **US D1,086,242 S**
(45) **Date of Patent:** **** Jul. 29, 2025**

(54) **PART OF INDUSTRIAL MIXER**

(71) Applicant: **THALETEC GmbH**, Thale (DE)

(72) Inventor: **Christian Stentzel**, Quedlinburg (DE)

(73) Assignee: **THALETEC GmbH**, Thale (DE)

(**) Term: **15 Years**

(21) Appl. No.: **35/520,537**

(22) Filed: **Feb. 6, 2024**

(80) **Hague Agreement Data**

Int. Filing Date: **Feb. 6, 2024**

Int. Reg. No.: **DM/236115**

Int. Reg. Date: **Feb. 6, 2024**

Int. Reg. Pub. Date: **Apr. 12, 2024**

(51) **LOC (15) Cl.** **15-09**

(52) **U.S. Cl.**

USPC **D15/138**
